US00D350800S

United States Patent [19]
Ota

[11] **Patent Number:** **Des. 350,800**
[45] **Date of Patent:** ** Sep. 20, 1994

[54] **IRON-TYPE GOLF CLUBHEAD**

[75] Inventor: **Dean Ota**, Irvine, Calif.
[73] Assignee: **Bost Enterprises, Inc.**, Westport, Conn.
[**] Term: **14 Years**
[21] Appl. No.: **781,024**
[22] Filed: **Oct. 18, 1991**
[52] U.S. Cl. **D21/220**
[58] Field of Search 273/167-175;
..... D21/220

[57] **CLAIM**

The ornamental design for an iron-type golf clubhead, as shown and described.

DESCRIPTION

FIG. 1 is a front view of a first embodiment of an iron-type golf clubhead showing my new design;
FIG. 2 is a top view of a first embodiment of an iron-type golf clubhead;
FIG. 3 is a left side view of a first embodiment of an iron-type golf clubhead;
FIG. 4 is a right side view of a first embodiment of an iron-type golf clubhead;
FIG. 5 is a rear view of a first embodiment of an iron-type gold clubhead;
FIG. 6 is a bottom view of a first embodiment of an iron-type golf clubhead;
FIG. 7 is a front view of a second embodiment of an iron-type golf clubhead;
FIG. 8 is a top view of a second embodiment of an iron-type golf clubhead;
FIG. 9 is a left side view of a second embodiment of an iron-type golf clubhead;
FIG. 10 is a right side view of a second embodiment of an iron-type golf clubhead;
FIG. 11 is a rear view of a second embodiment of an iron-type golf clubhead;
FIG. 12 is a bottom view of a second embodiment of an iron-type golf clubhead;
FIG. 13 is a front view of a third embodiment of an iron-type golf clubhead;
FIG. 14 is a top view of a third embodiment of an iron-type golf clubhead;
FIG. 15 is a left side view of a third embodiment of an iron-type golf clubhead;

(DESCRIPTIONS continued on next page.)

DESCRIPTION

FIG. 16 is a right side view of a third embodiment of an iron-type golf clubhead;
FIG. 17 is a rear view of a third embodiment of an iron-type golf clubhead;
FIG. 18 is a bottom view of a third embodiment of an iron-type golf clubhead;
FIG. 19 is a front view of a fourth embodiment of an iron-type golf clubhead;
FIG. 20 is a top view of a fourth embodiment of an iron-type golf clubhead;
FIG. 21 is a left side view of a fourth embodiment of an iron-type golf clubhead;
FIG. 22 is a right side view of a fourth embodiment of an iron-type golf clubhead;
FIG. 23 is a rear view of a fourth embodiment of an iron-type golf clubhead;
FIG. 24 is a bottom view of a fourth embodiment of an iron-type golf clubhead;
FIG. 25 is a front view of a fifth embodiment of an iron-type golf clubhead;
FIG. 26 is a top view of a fifth embodiment of an iron-type golf clubhead;
FIG. 27 is a left side view of a fifth embodiment of an iron-type golf clubhead;
FIG. 28 is a right side view of a fifth embodiment of an iron-type golf clubhead;
FIG. 29 is a rear view of a fifth embodiment of an iron-type golf clubhead;
FIG. 30 is a bottom view of a fifth embodiment of an iron-type golf clubhead;
FIG. 31 is a front view of a sixth embodiment of an iron-type golf clubhead;
FIG. 32 is a top view of a sixth embodiment of an iron-type golf clubhead;
FIG. 33 is a left side view of a sixth embodiment of an iron-type golf clubhead;
FIG. 34 is a right side view of a sixth embodiment of an iron-type golf clubhead;

FIG. 35 is a rear view of a sixth embodiment of an iron-type golf clubhead;
FIG. 36 is a bottom view of a sixth embodiment of an iron-type golf clubhead;
FIG. 37 is a front view of a seventh embodiment of an iron-type golf clubhead;
FIG. 38 is a top view of a seventh embodiment of an iron-type golf clubhead;
FIG. 39 is a left side view of a seventh embodiment of an iron-type golf clubhead;
FIG. 40 is a right side view of a seventh embodiment of an iron-type golf clubhead;
FIG. 41 is a rear side view of a seventh embodiment of an iron-type golf clubhead;
FIG. 42 is a bottom view of a seventh embodiment of an iron-type golf clubhead;
FIG. 43 is a front view of an eighth embodiment of an iron-type golf clubhead;
FIG. 44 is a top view of an eighth embodiment of an iron-type golf clubhead;
FIG. 45 is a left side view of an eighth embodiment of an iron-type golf clubhead;
FIG. 46 is a right side view of an eighth embodiment of an iron-type golf clubhead;
FIG. 47 is a rear view of an eighth embodiment of an iron-type golf clubhead;
FIG. 48 is a bottom view of an eighth embodiment of an iron-type golf clubhead;
FIG. 49 is a front view of a ninth embodiment of an iron-type golf clubhead;
FIG. 50 is a top view of a ninth embodiment of an iron-type golf clubhead;
FIG. 51 is a left side view of a ninth embodiment of an iron-type golf clubhead;
FIG. 52 is a right side view of a ninth embodiment of an iron-type golf clubhead;
FIG. 53 is a rear view of a ninth embodiment of an iron-type golf clubhead; and,
FIG. 54 is a bottom view of a ninth embodiment of an iron-type golf clubhead.
The broken line showing a fragmented shaft is for illustration purposes only.
